UNITED STATES PATENT OFFICE.

SIMON EICHBERG, OF CHICAGO, ILLINOIS.

IRONING BOARD.

Application filed June 11, 1925. Serial No. 36,411.

To all whom it may concern:

Be it known that I, SIMON EICHBERG, a citizen of the United States, residing at Chicago, in the county of Cook and State 5 of Illinois, have invented certain new and useful Improvements in Ironing Boards, of which the following is a specification.

Briefly stated, an important object of this invention is to provide an ironing board 10 which may be quickly and conveniently adjusted according to the height of the person using the board so as to overcome in a measure the fatigue which results from using an ironing board which is either too high or 15 too low.

A further and equally important object is to provide an ironing board which may be quickly collapsed and folded when not in use so that the same will occupy a com- 20 paratively small space and another object is to provide simple means whereby the board is firmly supported and prevented from collapsing.

Other objects and advantages will be ap- 25 parent during the course of the following description.

In the accompanying drawing forming a part of this application and in which like numerals are employed to designate like 30 parts throughout the same,

Figure 1 is a perspective of the improved ironing board in position for use;

Fig. 2 is a vertical sectional view through the same;

Fig. 3 is a detail transverse sectional view taken on line 3—3 of Fig. 2;

Figure 4 is a fragmentary side elevation of the ironing board collapsed;

Fig. 5 is a detail sectional view illustrating one of the legs and the means for adjusting the same;

Fig. 6 is a detail sectional view taken on line 6—6 of Fig. 5.

In the drawing, wherein for the purpose 45 of illustration is shown a preferred embodiment of the invention, the numeral 5 designates a board of any desired shape and size and which as shown in Fig. 1 is supported by a pair of legs, each leg consisting 50 of a lower substantially U-shaped section 6 and an upper section 7. Figure 2 plainly illustrates that each upper section 7 is hinged to the under side of the board 5 by 55 spring hinges 8, the springs of the hinges serving to urge the legs outwardly to their inclined positions as shown in Figure 1.

This gives the board stability. It will be seen with reference to Figure 2 that the under side of the board 5 may be notched as at 9 to receive the upper portions of the 60 legs when the same are swung outwardly to their board supporting positions. In addition to this the under side of the board may be provided with abutments or shoulders 10 for engagement by the legs when 65 swung outwardly to their operative positions. This firmly braces the connection between the legs and the board.

In carrying out the invention, the upper sections of the legs may be provided with 70 tongues 14 which are received in grooves in the opposed edges of the sides of the U-shaped members 6 whereby a sliding and adjustable connection is established between the upper and lower sections of the legs. 75 Particular attention is directed to the fact that a U-shaped locking device 18 is carried by each U-shaped section 6 and is adapted to be selectively received in notches in the adjacent tongues to hold the legs in ad- 80 justed positions.

Figure 1 clearly illustrates that the upper sections of the legs may be provided with graduations to indicate the positions of the 85 sockets 20 which receive the terminal portions of the U-shaped locking devices 18 whereby the locking devices may be easily and quickly inserted into the proper sockets. This also provides a means whereby the two 90 legs may be adjusted to the same length and the element of uncertainty removed. The bight portions of the several U-shaped locking devices are readily accessible and may be easily grasped by the operator when it is desired to disengage the locking devices 95 from the sockets 20 for changing the lengths of the legs.

The bight portions of the U-shaped sections are extended laterally beyond the sides or edges of the U-shaped sections so as to 100 provide firm supporting bases for the legs. This reduces the possibility of tipping to a minimum.

When it is desired to collapse the ironing board the legs may be swung into overlapping relation as shown in Fig. 4 and a rotatable latch 33 carried by one of the legs may be engaged with the other leg to hold the legs in place.

The invention forming the subject matter 110 of this application is capable of quick adjustment to various heights and this permits

the person ironing to work while standing up or sitting down.

The invention is capable of a wide variety of mechanical expressions and it is, therefore, to be understood that the form of invention herewith shown and described is to be taken merely as a preferred example of the same and that such minor changes in arrangement and construction of parts may 10 be made as will remain within the spirit of the invention and the scope of what is claimed.

Having thus described the invention, what is claimed is:

- 15 1. An ironing board comprising a body, legs hingedly connected thereto and consisting of upper sections having tongues and lower sections of U-shaped formation having sides positioned at opposite edges of said upper sections and being formed with 20 grooves slidably receiving said tongues,

said tongues being notched, U-shaped locking devices carried by said U-shaped sections and adapted to be extended into said notches of said tongues to hold the sections 25 in adjusted positions, the bight portions of said lower sections being extended beyond the sides of the lower sections to provide supporting bases.

2. The combination with an ironing 30 board, of legs hinged thereto and consisting of upper sections and lower U-shaped sections having sides slidably connected to the upper sections, and U-shaped locking devices slidably carried by said lower sections and adapted to engage said upper sections to hold the legs in adjusted positions, the bight portions of said locking devices constituting a means whereby the operator 35 may engage or disengage the U-shaped 40 locking devices.

SIMON EICHBERG.
